UNITED STATES PATENT OFFICE.

JOSEPH W. JONES, OF JOLIET, ILLINOIS.

ROTARY GAS-ENGINE.

1,282,429.

Specification of Letters Patent. Patented Oct. 22, 1918.

Application filed December 18, 1916. Serial No. 137,636. BEST AVAILABLE COPY

To all whom it may concern:

Be it known that I, JOSEPH W. JONES, a citizen of the United States, residing at Joliet, in the county of Will, State of Illinois, have invented certain new and useful Improvements in Rotary Gas-Engines; and I do hereby declare the following to be a full, clear, and exact description of the invention, such as will enable others skilled in the art to which it appertains to make and use the same.

This invention relates to a new and improved rotary reversible internal combustion engine with special reference to that type of rotary engine wherein there is provided a series of cylinders which may revolve about a central axis or shaft, or the cylinders may be held stationary and the shaft made to revolve.

One important object of the invention is to improve and simplify the general construction of engines of this character, wherein the delicate parts commonly employed are reduced to a minimum, all valves 25 and valve mechanism timing gear and water cooling devices being dispensed with.

The second important object of the invention is to provide an improved form of engine wherein there will be a complete 30 cycle of four operations in each cylinder during each revolution of the cylinders or shaft with reference to a certain movable part of said engine hereinafter called the valve plate.

The third important object is to provide 35 an improved engine that may be constructed in the form of a rotary type wherein all of the working parts will be readily and conveniently accessible for repairs, adjustment or replacement.

The fourth important object of the invention is to provide two sets of cylinders wherein both sets or either of them may be operated at will and wherein one set of 45 cylinders may be rendered inactive without affecting the operation of the remaining cylinders or causing them to lose efficiency through their operation the pistons in the idle cylinders; and wherein said idle cylinders and pistons continue to revolve so as not to destroy the centrifugal balance of the engine.

The fifth important object of the invention is the provision of an improved engine 55 wherein the engine may drive a shaft forward or backward and the shaft be started,

stopped or reversed without disconnecting the same from the machine it is driving, all of said movements being accomplished without shock or jar such as would work injury to the mechanism of the engine or the machine.

The sixth important object of the invention is to provide an engine wherein all of the working parts are inclosed in a single 65 chamber and capable of being thoroughly lubricated by the splash system and immersion in oil, thus also rendering them noiseless.

The seventh important object of the invention is to provide a compact, high-speed motor with a relatively small number of parts that can be cheaply constructed having a high power per unit of size and weight, and of the air-cooled cylinder type especially suitable for use in automobiles, although not limited to such use.

With the above objects in view, as will be hereinafter set forth, the invention consists in general of certain novel details of 80 construction and combinations of parts, hereinafter fully described, illustrated in the accompanying drawings and specifically claimed.

In the accompanying drawings like characters of reference indicate like parts in the several views, and:

Figure 1 is an outline top plan of an engine constructed in accordance with this invention.

Fig. 2 is an outline side elevation there.

Fig. 3 is a vertical median section through such an engine.

Fig. 4 is a horizontal section through the centers of the cylinders.

Fig. 5 is a view showing the inner face of the valve plate together with certain parts of the gearing.

Fig. 6 is a detail section through the eccentrics.

Fig. 7 is a section on the line 7—7 of Fig. 4.

Fig. 8 is a section on the line 8—8 of Fig. 4.

Fig. 9 is a section on the line 9—9 of Fig. 3.

Fig. 10 is a section on the line 10—10 of Fig. 3.

In carrying out the objects of the invention in the embodiment herein illustrated there is provided a shaft 10 and mounted revolubly with respect to this shaft is a car-

rier 11 whereon are provided a series of cylinders 12 having their axes radial with respect to said shaft. In each of these cylinders there is provided a piston 13 whereto is connected a rod 14 terminating at its inner end in an eccentric strap 15. Mounted revolvably on the shaft 10 is a sleeve 16 and fixed to this sleeve are certain eccentrics 17 while other eccentrics 18 are keyed to the shaft 10, each of said eccentric straps surrounding a respective eccentric. When all of the cylinders are in operation, sleeve 16 and shaft 10 are locked together, this being effected by means of a clutch member 19 fixed to the sleeve and a second clutch member 20 splined to the shaft and movable into and out of engagement with the member 19 by means of a lever 21. By this means, when the clutch members are out of engagement the cylinders having connection with the sleeve are rendered idle, there being no reciprocation of the pistons therein, and as will be explained, the explosive fluid may be cut off from these cylinders so that they will simply revolve about the axis of the engine.

In order to provide for the admission of explosive gases to the cylinders and the exhaust of burnt gases therefrom each cylinder has a single port, which may be in the end as shown at 22 in Fig. 4 and detail Fig. 8 or on the side as shown at 23 in Fig. 5 and detail Fig. 7. I have herewith shown a combination of both; the ports in one half the cylinders being located preferably in the ends thereof as at 22 while the remaining ports are preferably located at the side of each of the remaining cylinders as shown at 23. To properly control the distribution of these gases there is employed a valve plate 24 having a flange 25 extending over the ends of the cylinders. In the inner face of this valve plate is an exhaust groove 26 and an inlet groove 27 arcuate in formation and over which the ports 23 successively pass during operation. In the flange 25 are similar grooves, 28 being the exhaust groove and 29 the inlet groove.

The exhaust grooves are provided with ports 30 to which are connected pipes 31 joined to a ring box 32 mounted on an annular exhaust box 32^a and communicating therewith through ports 32^b. In like manner the inlet grooves are connected by pipes 33 to a ring box 34 mounted on the box 32^a and bearing against an annular supply chest or box 31^a through ports 34^b. These connections are made necessary by reason of the revolution of the valve plate.

In order to accomplish this revolution of the valve plate there is provided a differential gearing consisting of a gear 36 which is keyed to the shaft 10, a gear 37 revolvably mounted on this shaft and fixed to the carrier 11 and idler pinions 38 which are mounted on shafts 39 carried by a ring 40 secured to the valve plate 24. Now it will be seen that, if the shaft be held stationary the reciprocation of the pistons will effect revolution of the carrier with consequent revolution of the gear 37 which will operate the pinions so that they will revolve about the shaft at one half the speed of the carrier and in the same direction. In a similar manner, if the carrier be held stationary and the shaft released, the latter will revolve in an opposite direction and carry with it the gear 36 so that the valve plate will, through the action of the pinions, revolve backward at one half the speed of the shaft, and if both carrier and shaft are released they will revolve at the same speed in opposite directions and valve plate 24 and ring-gear 40 and gear 47 will remain stationary, the pinions 38 only turning on their axis allowing the engine to run "idle."

In order to effect the restraint of the shaft or carrier from movement there is provided on the gear 36 a brake drum 41 which is surrounded by a brake band 42 capable of being forced against the drum by a lever 43 (not shown). Similarly the carrier is provided with a brake drum 44 surrounded by a brake band 45 operated by a lever (not shown). Thus it will be seen either the shaft or carrier may be locked against movement and the engine may be thus operated backward or forward at will or may be suddenly reversed from full speed forward or backward without shock or jar to any of the parts, or both brakes may be thrown off and the engine started or permitted to run idle.

To effect translation of this revolution of the engine into available power the ring 40 which, it will be noted, revolves whenever the engine is in motion either backward or forward, carries a bevel gear 46 which meshes with a bevel gear 47 fixed on a shaft 48 supported in a suitable bearing 49 in a housing 50 covering all the gears and which may be used as an oil receptacle so that the gears may be run in oil and thus be practically noiseless, and also furnishing splash oiling for all the parts.

The sparking system employed herewith consists of a copper ring 51 carried by insulation 52 fixed to the valve plate 24. This ring receives current from a suitable spark coil or magneto (not shown) and from this ring extend conductors 53 leading to adjustable brushes 54 which lie in the paths of spark plugs 55 carried by the cylinders 12. By this means the relative rotation of the carrier and valve plate causes make and break engagement of the current in said plugs and brushes at predetermined intervals on rotation of said carrier and valve plate, causing explosions in the cylinders at the end of compression periods.

The engine may be started manually or by attaching any of the mechanical start

ers, or compressed air may be admitted to one of the intake grooves, either 27 or 28 by any suitable device preferably by duplicating 33 and 34, the device shown for supplying said intake grooves with the explosive mixture.

The air pressure admitted to said groove will enter the port of successive cylinders passing over said groove, forcing the piston

10 in said cylinder from the outer to the inner end and imparting movement to the engine, allowing the opposite groove to supply the remaining cylinders with explosive mixture in the regular way until explosions occur; 15 said device providing means for blocking the intake 33 by a check valve to prevent the compressed air from entering pipe 33.

It is obvious that many minor changes may be made in the form and construction 20 of this invention without departing from the material principles thereof. I do not, therefore, wish to confine myself to the exact form herein shown and described, but wish to include all such as properly come

25 within the scope claimed.

Having thus described the invention, what is claimed, is:—

1. In an explosive engine, a shaft, a carrier revoluble with respect to said shaft, 30 a series of cylinders fixed to said carrier, pistons in said cylinders having crank connection with said shaft, a differential gearing having one gear fixed to the shaft and a second gear fixed to the carrier and provided with pinions between the first mentioned gears, a valve plate carried by the pinions and controlling the admission of gases to and from said cylinders, and independent means to restrain the movement of 40 the shaft and carrier.

2. In an explosive engine, a shaft, a carrier revoluble with respect to said shaft, a series of cylinders fixed to said carrier and provided each with a port for the admission 45 and exhaust of gases, pistons in said cylinder having crank connection with said shaft, a differential gearing having one gear fixed to the shaft and a second gear fixed to the carrier and provided with idler pinions 50 connecting the first mentioned gears, a valve plate carried by the pinions and having arcuate inlet and exhaust passages wherewith said ports successively register, and independent means to restrain the movement 55 of the shaft and carrier.

3. In an explosive engine, a shaft, a carrier revoluble with respect to said shaft, a series of cylinders fixed to said carrier and provided each with a port for the admission 60 and exhaust of gases, pistons in said cylinder having crank connection with said shaft, a differential gearing having one gear fixed to the shaft, and a second gear fixed to the carrier and provided with idler pinions connecting the first mentioned gears, a valve

plate carried by the pinions and having arcuate plural inlet and plural exhaust passages, certain of said ports registering successively with one of the exhaust and one of the inlet passages and the remaining 70 ports registering successively with the other passages, and friction brakes arranged to independently restrain the movements of said shaft and carrier.

4. In an explosive engine, a shaft, a carrier revoluble with respect to said shaft, a series of cylinders fixed to said carrier and provided each with a port for the admission and exhaust of gases, pistons in said cylinder having crank connection with said shaft, 80 a differential gearing having one gear fixed to the shaft and a second gear fixed to the carrier and provided with idler pinions connecting the first mentioned gears, a valve plate carried by the pinions and having arcuate inlet and exhaust passages wherewith said ports successively register and means to disconnect certain of said pistons from said shaft.

5. In an explosive engine, a shaft, a carrier revoluble with respect to said shaft, a series of cylinders fixed to said carrier and provided each with a port for the admission and exhaust of gases, pistons in said cylinder having crank connection with said shaft, a differential gearing having one gear fixed to the shaft and a second gear fixed to the carrier and provided with idler pinions connecting the first mentioned gears, a valve plate carried by the pinions and having arcuate plural inlet and plural exhaust passages, certain of said ports registering successively with one of the exhaust and one of the inlet passages and the remaining ports registering successively with the other passages, and means to disconnect certain of said pistons from said shaft.

6. In an explosive engine, a housing, a shaft, a carrier revoluble with respect to said shaft, a series of cylinders fixed to said carrier and provided each with a port for the admission and exhaust of gases, pistons in said cylinder having crank connection with said shaft, by means of two sets of cams, one set of cams fixed to said shaft and one set of cams fixed to a sleeve revoluble on said shaft with means for making said sleeve rigid with said shaft, a differential gearing having one gear fixed to the shaft and a second gear fixed to the cylinder carrier and provided with idler pinions meshing with the first mentioned gears, a valve plate carried by the pinions having arcuate plural inlet and plural exhaust passages with means for supplying said inlet passages with explosive mixture the ports of certain cylinders registering successively with one of the exhaust and one of the inlet passages, and the ports of the remaining cylinder registering successively with the other passages,

and means for shutting off the supply of explosive mixture to one of the inlet passages, and means for firing said explosive mixture at predetermined times.

5. In an explosive engine, a housing, a valve having arcuate plural inlet and plural exhaust passages movably mounted with respect to said housing, a carrier plate carrying a multiple of cylinders movably mounted with respect to said valve plate; the said cylinders each with a port for the admission and exhaust of gases in and through said plural exhaust passages in said valve plate, pistons in said cylinders having operative connection through eccentric straps with a shaft perpendicular to said cylinders, said shaft having two sets of cams one set of cams fixed to said shaft and one set of cams fixed to a sleeve revolvable on said shaft with means for making said sleeve rigid with said shaft, a differential gearing having one gear fixed to the shaft and a second gear fixed to the cylinder carrier and provided with idler pinions meshing with the first mentioned gears, the valve plate carried by the pinions with means for supplying said inlet passages with explosive mixture the ports of certain cylinders registering successively with one of the exhaust and one of the inlet passages, and the ports of the remaining cylinders registering successively with the other passages, means for shutting off the supply of explosive mixture to one of the inlet passages, and means for firing said explosive mixture at predetermined times.
8. In an explosive engine, a housing, a valve plate having arcuate plural inlet and plural exhaust passages and mounted to rotate on said housing, a carrier mounted to rotate on the valve plate, a plurality of cylinders attached to the carrier and pistons in said cylinders having operative connection with a shaft perpendicular to said cylinders, a differential gearing mounted on said shaft, one gear of which is fixed to the shaft and the opposite gearing fixed to said cylinder carrier and the idler pinions of said differential gearing fixed to the valve plate.
9. In an explosive engine, a housing, a shaft, a carrier revolvable with respect to said shaft, a series of cylinders fixed to said carrier, pistons in said cylinders having operative connection with said shaft, a differential gearing having one gear fixed to said carrier and a second gear fixed to the shaft and pinions between the first mentioned gears, a valve plate carried by the pinions and controlling the admission of gases to and from said cylinders, and means to control the movement of said valve plate.
10. In an explosive engine, a housing, a perpendicular shaft in said housing, two gears mounted on said shaft, one of said gears being fixed and one rotatable with respect to the shaft, pinions in mesh between the said gears, a ring gear carried by said pinions, a valve plate attached to said ring gear and rotatably mounted on said housing, a carrier plate rotatably mounted on said valve plate, a series of cylinders rigidly mounted on said carrier, pistons in said cylinders having operative connection with said shaft, each of said cylinders having ports, said valve plate having exhaust and inlet passages with which said ports register, and independent means to selectively restrain the movement of the shaft and carrier.
11. In an explosive engine, a housing, a shaft revolvable in said housing, a valve plate revolvable with respect to said shaft and housing, a carrier plate slidably mounted on said valve plate, a series of cylinders fixed to said carrier, pistons in said cylinders, eccentrics fixed to said shaft, a fractional number of said pistons having operative connection with said eccentrics, a sleeve on said shaft, other eccentrics fixed on said sleeve, the remainder of said pistons having operative connection with the last mentioned eccentrics, and means for causing said sleeve to revolve with said shaft.
12. In an explosive engine, a housing, a valve plate having arcuate plural inlet and plural exhaust passages and revolvably mounted with respect to said housing, a carrier plate slidably mounted with respect to said valve plate, a series of cylinders fixed to said carrier and provided each with a port for the admission and exhaust of gases, said ports registering periodically with said passages in said valve plate, a shaft perpendicular to said cylinders, pistons in said cylinders having operative connection with the shaft, and means for disconnecting certain of said pistons from operative connection with said shaft.
13. In an explosive engine, a housing, a valve plate having plural inlet and exhaust passages rotatably mounted with respect to said housing, a carrier plate rotatably mounted with respect to said valve plate, a series of cylinders provided with ports and fixed to said carrier plate, the ports of certain of the cylinders registering successively with one of the exhaust and one of the inlet passages in said valve plate, and the ports of the remaining cylinders registering successively with the other exhaust and inlet passages of said valve plate, means for supplying said cylinders with explosive mixture through said valve plate, a shaft perpendicular to said cylinders, pistons in said cylinders operatively connected with the shaft, and means for disconnecting a fractional number of said pistons from operative connection with the said shaft.
14. In an explosive engine, a housing, a shaft, a carrier revolvable with respect to said shaft, a plurality of cylinders fixed to said carrier and provided each with a port for

BEST AVAILABLE COPY

the admission and exhaust of gases, pistons
in said cylinders having operative connec-
tion with said shaft, a differential gearing
having one gear fixed to the shaft and a
5 second gear fixed to the carrier and pro-
vected with idler pinions connecting the first
mentioned gears, a ring gear carried by
said idler pinions, a valve plate carried by
the ring gear and having arcuate plural in-
10 let and plural exhaust passages, the ports
of certain of said cylinders registering suc-
cessively with one of the exhaust and one of
the inlet passages and the ports of the re-
maining cylinders registering successively
with the other passages, and means for dis- 15
connecting certain of said pistons from op-
erative connection with said shaft.

In testimony whereof, I affix my signa-
ture, in the presence of two witnesses.

JOSEPH W. JONES.
